(57) **CLAIM**

The ornamental design for a buoy badge for a swim goggle, as shown and described.

DESCRIPTION

FIG. 1 is a right side elevational view of the buoy badge for a swim goggle of the present invention showing our new design in use;

FIG. 2 is a front elevational view thereof;

FIG. 3 is a top plan view thereof;

FIG. 4 is a front elevational view thereof;

FIG. 5 is an end view thereof;

FIG. 6 is a bottom plan view thereof;

FIG. 7 is a rear elevational view thereof;

FIG. 8 is a front elevational view thereof depicting the buoy badge for a swim goggle of the present invention in an open configuration; and,

FIG. 9 is a front elevational view thereof depicting the buoy badge for a swim goggle of the present invention in an open configuration.

The broken lines shown in the figures included for the purposes of illustrating environmental structure and unclaimed portions of the buoy badge for a swim goggle, and form no part of the claimed design.

The smaller dotted lines shown in FIGS. 2, 4, 7, 8 and 9 represent stitching on the buoy badge for a swim goggle, and form part of the claimed design.
